C. W. FAILOR

RAILWAY TRAFFIC CONTROLLING APPARATUS

Filed May 6, 1927

UNITED STATES PATENT OFFICE.

CHARLES W. FAILOR, OF PITTSBURGH, PENNSYLVANIA, ASSIGNOR TO THE UNION SWITCH & SIGNAL COMPANY, OF SWISSVALE, PENNSYLVANIA, A CORPORATION OF PENNSYLVANIA.

RAILWAY-TRAFFIC-CONTROLLING APPARATUS.

Application filed May 6, 1927. Serial No. 189,269.

My invention relates to railway traffic controlling apparatus, and particularly to apparatus of the type wherein alternating train governing energy is periodically applied to the track rails for the control of train-carried governing mechanism. The present invention relates to the trackway portion of such apparatus, and specifically to track circuits in which the source of track circuit current is located at the entrance end of the section and the track relay is located at the exit end.

I will describe one form of apparatus embodying my invention, and will then point out the novel features thereof in claims.

The accompanying drawing is a diagrammatic view showing one form of apparatus embodying my invention. Referring to the drawing, the reference characters 1 and 1^a designate the track rails of a railway along which traffic normally moves in the direction indicated by the arrow. These rails are divided by insulated joints 2 into a plurality of track sections, the complete apparatus for only one track section A—B being shown in the drawing. This section is provided with a track circuit comprising a transformer T^a located at the entrance end of the section, and a track relay R located at the exit end.

The secondary 3 of transformer T^a is connected across the track rails through a limiting impedance 28, and the primary 4 of this transformer is connected with the secondary 5 of a line transformer L^a. The primary 6 of the line transformer L^a is constantly supplied with alternating current from a generator G through the medium of a transmission line M.

The track relay R comprises two windings 8 and 9 and a rotor 7. One terminal of winding 8 is connected with track rail 1^a, and the other terminal of winding 8 is connected with track rail 1 through a front contact 10 of the relay R. The other winding 9 is constantly supplied with alternating current from the secondary 5 of a line transformer L^b, the primary 6 of which is connected with a transmission line M. It will be seen from the foregoing that when the track relay R is open, it cannot be closed unless a shunt path around contact 10 is closed, but that when the relay R is once closed it will remain closed as long as track circuit current is

supplied to the track rails, because the circuit for winding 8 is then completed through front contact 10.

Alternating train governing current is supplied to the rails at the exit end of section A—B by a transformer D, the secondary 25 of which is connected across the rails through a limiting impedance 27, and the primary 26 of which is at times supplied with alternating train governing current which is periodically interrupted by a coding device C.

The coding device C comprises a motor 16 operating two cams 17 and 18. Co-acting with the cam 17 is a rocker arm 23 which actuates two contacts 19 and 20. When the motor 16 is in operation these two contacts are alternately closed, and they are so arranged that each contact is open while the other contact is closed. Co-acting with the cam 18 is a second rocker arm 24 which actuates another pair of contacts 21 and 22 in such manner that these contacts are alternately closed and that each contact is open while the other contact is closed. The two cams 17 and 18 have different numbers of swells, so that for each complete revolution of these cams, contact 20 will be closed once whereas contact 22 will be closed four times.

The reference character H^a designates a home relay located at the entrance end of section A—B and supplied with alternating current from a secondary 5 of transformer L^b through the first contacts 12 and 13 of relay R. It follows that relay H^a will be closed or open according as track relay R is closed or open. The track section to the right of point B is provided with a home relay H^b which is controlled in the same manner as relay H^a.

The motor 16 of the coding device C is provided with a circuit which passes from the secondary 5 of transformer L^b, through back contact 11 of track relay R, and the motor 16 to secondary 5. It follows that motor 16 will be in operation when and only when track relay R is open. When relay R is open, current is supplied to the primary 26 of transformer D through contact 20 or 22 of the coding device C according as home relay H^b is open or closed. Assuming that relay H^b is closed, the circuit for primary 26 is from secondary 5 of transformer L^b, through back contact 11 of track relay R,

front contact 14 of relay H^B , contact 22 of coding device C, and the primary 26 of transformer D to secondary 5 of transformer L^B . If relay H^B is open, the circuit will be the same except that it will include back contact 14 of relay H^B and contact 20 of coding device C.

- 10 The front contact 10 of relay R is provided with a shunt which includes contact 19 or 21 of the coding device C according as relay H^B is open or closed. Assuming first that relay H^B is closed, this shunt passes from the heel of contact 10, through front contact 15 of relay H^B and contact 21 of coding device C to the toe of contact 10. If relay H^B is open, the shunt is the same except that it includes the back point of contact 15 of relay H^B and contact 19 of the coding device C.
- 15 20 It will be seen from the foregoing that when the coding device C is in operation, alternating train governing current will be supplied to the rails of section A—B, and that this current will be periodically interrupted at one frequency or another according as relay H^B is closed or open; and it will also be seen that a shunt around contact 10 of relay R is closed during each interval between applications of train governing current to section A—B.

25 The operation of the apparatus is as follows:

30 When the section A—B is unoccupied and track relay R is closed, the circuit for motor 16 of the coding device C is open at contact 11 and so this device is at rest. I will now assume that a train moving toward the right enters section A—B. The wheels and axles of this train constitute a shunt across the 35 track rails and so the supply of track circuit current to winding 8 of relay R is discontinued. This relay accordingly opens, and motor 16 then becomes energized to 40 operate the coding device C. Train governing current is then supplied to the rails of section A—B, which current is periodically interrupted at one frequency or another according as relay H^B is closed or open, that is, according as the section next to the right 45 is unoccupied or occupied. With contact 10 of relay R^B open, the train governing current cannot energize winding 8 to close this relay. Furthermore, the shunt around contact 10 of relay R is closed only 50 at such times as train governing current is not being supplied to section A—B, so that there is no current present in the track rails to energize relay R while this shunt is closed. The first time that the low resistance shunt 55 around contact 10 of relay R becomes closed after the train passes out of the section A—B, this relay will become energized due to track circuit current from transformer T^A , and will thereafter remain energized as 60 long as the section is unoccupied, because 65

its front contact 10 is now closed. The opening of contact 11 will discontinue the supply of current to the motor 16 and so the coding device will come to rest.

70 Although I have herein shown and described only one form of apparatus embodying my invention, it is understood that various changes and modifications may be made therein within the scope of the appended claims without departing from the 75 spirit and scope of my invention.

Having thus described my invention, what I claim is:

1. In combination, a section of railway track, a source of track circuit current connected with the rails adjacent the entrance end of said section, a track relay connected with the rails adjacent the exit end of said section through its own front contact, means including a motor and a contact operated thereby for periodically applying train governing current to the track rails at the exit end of the section, and means operated by said motor for closing a shunt around said front contact of the track relay during each 80 interval between applications of train governing current but not during the application of train governing current.
2. In combination, a section of railway track, a source of track circuit current connected with the rails adjacent the entrance end of said section, a track relay connected with the rails adjacent the exit end of said section through its own front contact, a motor, a first contact controlled by said 85 motor and arranged to be alternately closed and opened while the motor is in operation, a second contact controlled by said motor and arranged to be open while the first motor controlled contact is closed and closed while the first contact is opened, means including said first contact for applying train governing current to the rails at the exit end of said section, and a shunt path around said track relay front contact including said 90 second motor controlled contact.

3. In combination, a section of railway track, a source of track circuit current connected with the rails adjacent the entrance end of said section, a track relay connected with the rails adjacent the exit end of said section through its own front contact, a motor, two contacts controlled by said motor and arranged to be alternately closed while the motor is in operation, each contact being 100 open when the other contact is closed, means including one of said motor controlled contacts for applying train governing current to the track rails at the exit end of the section, and a shunt path around said track relay front contact including the other 105 motor controlled contact.

110 In testimony whereof I affix my signature.

CHARLES W. FAILOR.
